UNITED STATES PATENT OFFICE.

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY.

SORTING MACHINE.

Application filed March 7, 1925. Serial No. 13,722.

This invention relates to machines adapted for sorting perforated record cards used in tabulating systems, such, for instance, as the Hollerith.

5 My present invention is an improvement on the machine described in detail in my co-pending application, Serial No. 751,060, which discloses a sorter of the horizontal type designed to sort cards electrically and 10 deposit each predetermined class in its proper station.

It is frequently desirable to select from a promiscuous stack of cards those belonging to a certain group, and then to sort the 15 cards of that group into various sub-group classifications. Heretofore, in order to accomplish this result it has been necessary to first run the entire stack of cards through a sorter to first segregate the group desired, 20 and then run the cards of that group through the sorter again in order to make the final classification.

My present invention enables the above 25 result to be obtained in a single run of the cards, by removing at the first sorting station all cards not belonging to the desired group, and letting the cards of the group pass on to be classified by the regular single column sorting stations in the usual manner.

30 The perforations designating group numbers are usually in a plurality of columns on the card, so I provide at the first station a device capable of analyzing plural-column combinations of holes. This device senses 35 the perforations in the group control section of the card. If the perforations do not indicate that the card belongs to the desired group, it is directed into the first station by the deflector at that station, which is normally in deflecting position. If, however, the 40 perforations show that the card does belong to the predetermined group, the deflector is thereupon shifted to non-deflecting position and the card passes on to be sorted or classified by the single-column sorters in the usual manner.

45 My machine may also be used for regular single-column selecting or sorting, or it may be used for simply segregating the cards of 50 a group without the additional single column sorting, as will be later explained.

Further and other advantages of the present invention will hereafter appear in the accompanying drawings and specifica-

tions, which, by way of illustration show what I now consider to be a preferred embodiment of the invention.

In the drawings

Fig. 1 is a front elevation, partly broken away, of my complete machine.

60 Fig. 2 is a side sectional elevation of the feed mechanism and the control devices at the first station.

Fig. 3 is a side sectional elevation of some single-column sorting stations, conveyor 65 system, etc.

Fig. 4 is a plan view of the sensing devices at the first and second stations.

Fig. 5 is an enlarged side sectional elevation of the electric sensing device at the first 70 station, taken on line 5—5 of Fig. 4.

Fig. 6 is a sectional elevation of the sensing device at the first station, on line 6—6 of Fig. 4.

Fig. 7 is a typical Hollerith card.

75 Fig. 8 is a detail view showing how the conveyor rolls are driven.

Figs. 9 and 9^a taken together show the electric circuits.

Referring to Fig. 1, the frame 30 is 80 mounted on legs 31. Underneath the main frame, and carried by the legs, is a shelf or subframe 32 supporting the motor 33, which drives the machine from pulley 34 by belt 35 to pulley 36 fast to shaft 37, which runs 85 the full length of the machine, in the rear, pulley 36 being on one end of it and hand-wheel 38 on the other.

In operation a stack of cards to be sorted is placed in the feed magazine, as at 55, the 90 operator adjusts the analyzing brushes, and when the motor is started the picker drum feeds the cards, one by one, from the bottom of the stack into the conveyor rolls which carry them along horizontally above the 95 receiving stations until each card is deflected downwardly into one of the receiving stations, which are fully described in the co-pending application above referred to.

The feed mechanism consists of the rotary 100 picker drum 61, driven from shaft 37. Drum 61 carries in its rim a number of picker blades 69 extending lengthwise of the drum and projecting therefrom a distance slightly less than the thickness of a card. As the 105 drum revolves, each blade in turn picks a card from the bottom of the stack 55 and feeds it through the micrometer openings

72 provided between the bottom of fixed plate 73 and rollers 74, into the control of the conveyor rolls.

The upper conveyor rolls are designated 82, there being two of them fast on each shaft 83, while directly under each of these rolls is a lower roll 84 fast on shaft 85. The rolls are driven by worms 86 on shaft 37, through worm gears 87 fast on shafts 83 and 85. All rolls are driven at the same speed and are of the same diameter, the upper sets turning clockwise and the lower sets counter-clockwise so as to draw the cards between them. Each upper pair of rolls is downwardly-spring-pressed against the corresponding lower set by adjustable spring clips 92. It is found that this conveyor system insures that the exact distance between cards will be maintained throughout their travel, 20 which is an essential feature in the operation of my invention.

A typical Hollerith record card is shown in Fig. 7. The card is divided by vertical lines into various sections in each of which 25 information or data is punched according to the requirements of the particular industry or business in which the card is used. We are interested especially in that section 30 of the card marked "Group", in which section are punched holes designating numbers of various groups into which it may be desirable to classify the cards. It will be noted that the group number in the card shown in Fig. 7 is 785021.

35 In the embodiment of my invention herein described, the card, on being fed from the stack, passes first to the plural-digit analyzing device, where it is either deposited in the first station, or, if it belongs to the pre-determined group, is passed on for further analysis at the succeeding single column stations, which are designated 9, 8, 7, 6, 5, 4, 3, 2, 1, 0, and R, in the order named.

Crosswise of the machine between the card 45 feeding device and the first receiving station are a pair of horizontal threaded shafts 101 and 102, one directly above the other, and both parallel to conveyor shafts 83 and 85. These shafts are supported in bearings in 50 the frame of the machine and are geared together by the gears 103 and 104 so that when the hand crank 105 is turned both shafts will rotate. Mounted on the upper shaft 101 is a horizontal brush frame 106 carried by threaded bosses 107 on shaft 101. Brush plate 106 is held in stable horizontal position by the two extensions 108, one at 55 each end, which bear against the under sides of the nearest shafts 83.

60 Directly underneath brush frame 106 and carried on shaft 102 by threaded bosses 109, is the insulated contact frame 110, which is held in stable horizontal position by angle pieces 111 resting on top of adjacent conveyor shafts 85.

Shafts 101 and 102 turn in opposite directions on account of being connected by spur gears. But shaft 101 is right threaded and shaft 102 left threaded, so when crank 70 105 is actuated, brush plate 106 and contact plate 110 move together crosswise of the machine and will always remain in fixed relationship to each other.

Imbedded in the upper surface of plate 110 are a plurality of parallel metallic contact strips 112 extending lengthwise of the machine and so spaced as to correspond to the columns on the card. Plate 106 has formed in it a plurality of parallel slots 113 formed by bars 114. Each slot 113 is directly above a contact strip 112, and fitted in each slot is an insulated brush holder 115 carrying a contact brush 116 which is normally in contact with its corresponding strip 112, or with the top surface of a card if a card be passing through. Each brush holder may be moved longitudinally in its slot and held at any one of a plurality of positions by its spring clip 117, fitted into a notch 118 on bar 114. Each notch 118 corresponds to a digit position on the record card, as indicated by the numbers in Fig. 4. Each brush 116 has a plug socket 119 which may be connected electrically to any other plug socket 119 by wires 120 carrying plug taps 121 at each end. In Fig. 4 it will be noted that the brushes are so positioned as to read 785021, which is the same group control number as is shown in the card in Fig. 7.

Crosswise of the frame of the machine and fastened thereto at their ends are a plurality of rods 125. These rods are parallel to shafts 83 and in approximately the same plane. Each rod carries a brush holder 126 of non-conducting material, settable lengthwise on rod 125 and secured thereto by set screws 127 or other means. Each brush holder 125 carries a contact brush 128 which bears on the top surface of cards passing between the conveyor rolls. Rods 125 are so positioned lengthwise of the machine that each card passes under a brush 128 just before it reaches each receiving station. If no card be present the lower end of the brush rests on a metallic contact strip 129, supported by non-conducting brackets 130 rigidly secured to the frame of the machine.

Cards are fed into my sorter bottom first, so the index positions on the card pass through the rolls and under the brushes in the order 9, 8, 7, 6, 5, 4, 3, 2, 1, 0. Brushes 128 and contact strips 129 are so located differentially lengthwise of the machine that when cards are passing through the rolls, if the first brush (counting from the right) rests on the No. 9 index position on the card, the second brush will rest on No. 8, the third on No. 7, and so on. This is illustrated in Figs. 2 and 3 and is also shown diagrammatically in Figs. 9 and 9a.

Adjacent the first receiving station is a magnet 135 which, when energized actuates a curved deflector plate 136, hinged on rod 137 and fast to arm 138 which carries armature 139. When arm 138 is actuated the pin 140 in the free end of that arm, moves spring blade 141 to make contact in the stick circuit at 142. This stick circuit keeps the magnet energized and the deflector down until the card has passed. Arm 138 and its armature 139 are normally held away from magnet 135 by spring 143 acting on vertical arm 144 which is rigidly connected to arm 138.

Adjacent each of the single-brush sorting stations is a magnet 145, which when energized, raises its deflector 146, hinged on rod 147 and fast to arm 148 which carries armature 149. When arm 148 is actuated its pin 150 moves spring blade 151 to make contact in the stick circuit at 152. Spring 153 holds armature 149 normally away from magnet 145.

It will be noticed that in its normal position the upper end of deflector 136 at the plural-column station is above the plane of passing cards, so that while its magnet 135 is de-energized all cards will go into the pocket under that deflector. When magnet 135 is energized the deflector will be lowered and while in that position all cards will pass by that station.

On the other hand, at all single-column stations the normal position of the deflector 146 is below the plane of passing cards and it is only while a magnet 145 is energized that its deflector 146 will intercept cards and direct them into its corresponding pocket. In Fig. 2 the plural-column deflector 136 is shown in normal (raised) position, while in Fig. 3 the center deflector 146 is in its normal (depressed) position.

On the same shaft with picker drum 61 is a gear 160 geared in the ratio 4 to 1 to the smaller gear 161, so that gear 161 makes one revolution for each card fed from the stack. Secured to gear 161 is the cam 162 operating against spring blade 163, to make and break contact 164. This illustrates only part of the cam contact mechanism, which is the conventional cam and contact device used in tabulating and sorting machines, driven synchronously with the card movement to make the brush circuit just before a perforation reaches the brush and break the circuit just before the brush leaves the perforation in the card, to thereby prevent arcing at the card. This device is shown diagrammatically in Fig. 9^a, at the left.

On the same shaft with gear 161 is also located a cam 165, shown diagrammatically in Fig. 9^a. This cam also operates synchronously with the card feed and serves to interrupt the relay "stick" circuits 166 (Fig. 9^a) just before the brush leaves the trailing end of the card. Manually operated

switches 167 are provided in each brush circuit for breaking any brush circuit if desired.

Referring to Figs. 9 and 9^a, current is supplied to the line through switch 170. The motor is started by pressing start key 171, and stopped by pushing either stop key 172, one of which is located at each end of the machine. When 171 is closed, current flows through line 173, stop keys 172, start key 171, line 174 and back to source 170 through line 175. This energizes magnet 176 and a motor stick circuit is established through line 177. At the same time magnet 178 is energized, and if key 171 be held depressed until a card is under the card control lever, represented conventionally at 179, contact 180 will be closed and a stick circuit established around the start key 171 through contact 180. Current flows to the sorting magnets through line 181 and back through return line 182. If either stop key 172 be depressed, or if card lever contact 180 be opened by the supply of cards failing, current to the sorting magnets and to the motor will be interrupted and the machine will stop.

The operation of my machine will be readily understood if we consider first the single-column sorting stations and their action, assuming for the moment that the group-control (first) station is letting all cards go by for sorting into the single-column receiving pockets 9, 8, 7, 6, 5, 4, 3, 2, 1, 0, and Reject.

Before beginning to sort a stack of cards the operator adjusts all the single column brushes by setting their holders 126 on rods 125 so that each brush will traverse a card column being analyzed. One card column is analyzed by each brush and that column has a hole punched in it at some index point, or the column has no hole at all.

While my sorter is in operation contact is made at 164 once for every card cycle, and that contact is made at the instant the card or cards are in the positions indicated in Figs. 9 and 9^a or shown in Figs. 2 and 3, which means that, due to their differential locations, the brush controlling the deflector of station No. 9 is resting on the No. 9 index position on the card column under it; brush controlling No. 8 deflector is resting on No. 8 index position on its card; No. 1 brush is resting on No. 1 position; and so on, each brush resting on the index position corresponding to its particular compartment or station. Now it is apparent that if there be a hole in a card at any index position, the brush resting on that position will make contact through the hole with its contact strip 129, so that when the circuit is completed by contact at 164 the magnet controlled by that particular circuit will be energized, its deflector raised, and the card

when it advances further will be deposited in the compartment under that deflector. This condition is shown in Fig. 3 wherein the brush to the right has contacted with the plate 129 through a hole in the card. This has operated the deflector above the next station and it is evident that further progress of the card through which contact was made, will take it into that compartment, where it belongs.

The brush controlling No. 9 station searches only for holes in the 9 position on the card; brush No. 8 searches only for holes in the 8 position, and so on. If a brush finds a hole at its particular position it acts, otherwise it lets the card pass on to be examined at each succeeding station. If no hole be found at any index position in the column being examined the card will pass to the final station, marked R, or "Reject".

As the card is moving rapidly, contact by brush 128 is only momentary, but sufficient to operate the magnet and its deflector. In order to hold the deflector in raised position until the card has reached the station, I provide that whenever a magnet 145 is energized it closes contact 152 thereby providing a stick circuit which keeps magnet 145 energized until broken by cam 36 165 (Fig. 9a).

Considering now the "group control" or plural column analyzing station through which the cards must pass before reaching the single column stations, the operator sets his contact brushes, in brush frame 106, and connects them with wires 120, as already explained, so that if a card punched with the predetermined group number is under those brushes when the impulse is sent 40 through the line by contacts 164, magnet 135 will be energized and deflector 136 lowered so that the card will pass along for sorting by the regular single column stations.

I have illustrated this in the drawings by 45 a concrete example, assuming a group number 785021. Fig. 4 shows a top view of the brush plate, brush holders, and wires so arranged as to spell that number. Contact strips 112 are also suitably connected by 50 wires 190 through plugs 191 (Figs. 2 and 9). This setting is shown diagrammatically in Fig. 9.

If now brush plate 106 and contact plate 110 are positioned by turning hand crank 55 105 so that the group control section of the card (Fig. 7) passes under the brushes it is evident that whenever the particular combination of perforations indicating 785021 is under the brushes when the current impulse is sent through the magnet control line 181-182, a series circuit is set up through line 192 (Fig. 9), lower contact strip 112, brush 116 at the 1 position, to the second brush 65 through wire 120, to the second contact strip, from which it passes by wire 190 to the

third strip, from which it passes by the brush at 0 position to the next brush, at 5 position, and so on, finally emerging from the upper strip through wire 193 to magnet 135 which draws down deflector 136, permitting 70 the card to pass on.

It is plain that only the particular combinations of holes indicating the predetermined group number will allow such a circuit to be set up, because any other combination of 75 holes will find at least one brush resting on a blank portion of the card. Hence, every card of the desired group will pass on, and every card not of that group will be deposited in the first receiving compartment because 80 it will fail to permit energization of magnet 135.

As soon as magnet 135 is energized and arm 138 drawn down a "stick" circuit is 85 established from 192 through 138, line 166, to line 193, which circuit holds until broken by cam 165 at the end of the card cycle.

In case it is desired to use my machine for straight sorting, without group control, 90 switch 194 is closed, which permits energization of magnet 135 every time contact 164 is closed, regardless of the card perforations, so every card will pass the group control station.

If, on the other hand, the operator wants 95 the cards of a group segregated from a promiscuous stack of cards but does not want them sorted into sub-classes by the single column stations, he opens switch 194 and all 100 single column switches 167. With such a setting all cards not of the predetermined group will go into the first station, and all cards belonging to the group will pass on unhindered, to the final, or R station.

I claim:

1. In a machine for sorting cards having index perforations, in combination, a series 110 of receiving stations, means at one station for making a preliminary analysis of the perforations in the cards, and means at each succeeding station for making further analysis of a type different from the preliminary analysis of said perforations.

2. In a machine for sorting cards having index perforations, in combination, a plurality of receiving stations, conveying means to carry cards to said stations successively, means at one station for making a preliminary analysis of plural-column combinations of holes in the cards, and means at succeeding stations for making further analysis of a type different from the preliminary analysis, in the same run, of index perforations in cards which have passed said first station.

3. In a machine for sorting cards having index perforations, in combination, a series of receiving stations, means to convey cards to said stations successively, means at the first station to permit passage only of cards having certain predetermined perforations,

and means at succeeding stations to analyze and distribute said cards into the succeeding stations.

4. In a machine for sorting cards having index perforations, in combination, a plurality of receiving stations, means at one station for sensing the perforations in the cards by causing electric current to flow through holes in the cards, and similar means at each succeeding station for further sensing the perforations in cards which have passed said first sensing means.

5. In a machine for sorting cards having index perforations, in combination, a plurality of receiving stations, means to convey cards to said stations successively, means at one station for analyzing plural-column combinations of holes in the cards by causing electric current to flow through holes in the cards, and means at succeeding stations to further analyze by electric contacts through the card perforations, in the same run, index perforations in cards which have passed said first station.

25 6. In a machine for sorting cards having index perforations, in combination, a series of receiving stations, means at one station for making a preliminary examination of the perforations in the cards while the cards are in motion, and means at each succeeding station for making further examination of said perforations while the cards are in motion.

35 7. In a machine for sorting cards having index perforations, in combination, a series of receiving stations, means at one station for making a preliminary analysis of the perforations in the cards by electric contacts through said perforations, and means at each succeeding station for making further analysis of said perforations; all said analyzing operations being performed while the cards are in motion.

45 8. In a machine for sorting cards having index perforations, in combination, a plurality of receiving stations, means to convey cards to said stations successively, electric contact means at one station to analyze plural-column combinations of holes in the cards while the cards are in motion, and electric contact means at succeeding stations to further analyze, in the same run, while the cards are in motion, index perforations in cards which have passed said first station.

55 9. In a machine for sorting cards having index perforations, in combination, a series of receiving stations, means to convey cards to said stations successively, means at the first station to permit passage only of cards having certain predetermined perforations, and means to subsequently analyze and distribute said cards into the succeeding stations.

65 10. In a machine of the class described, in combination, a series of receiving stations,

electrically controlled means at the first station to permit passage only of cards having certain predetermined perforations, and electrically controlled means to subsequently analyze and distribute said cards into the 70 succeeding stations.

11. In a machine of the class described, in combination, means for feeding perforated record cards bearing group designations, a series of analyzing stations, means at the first station to permit passage only of cards of a predetermined group, and means at the succeeding stations to further analyze the cards of the group.

12. In a machine of the class described, in combination, means for feeding perforated record cards bearing group designations comprising perforations in one or more columns on the cards, a plurality of card analyzing stations, means at the first station to permit passage only of cards of a predetermined group, and means to pass the cards of said group through the other stations for further analysis.

13. In a machine for sorting cards having index perforations, in combination, a series of receiving stations, a device at one station for making a preliminary analysis of the perforations in the cards, and a device at each succeeding station for making further analysis of the perforations, each of said analyzing devices comprising one or more contact brushes and their corresponding contact pads.

14. In a machine of the character described, in combination, a series of receiving stations, analyzing means including a control circuit at each station, a magnet in each control circuit, and a deflector at each station controlled by said magnet, each deflector at all stations except the first being normally in non-deflecting position but movable to deflecting position when its magnet is energized, the deflector at the first station being normally in deflecting position but movable to non-deflecting position when its magnet is energized.

15. In a machine of the character described, in combination, a plurality of receiving stations, analyzing means including a control circuit at each station, a magnet and one or more contact brushes in each control circuit, and a deflector at each station controlled by said magnet, the first deflector being normally in deflecting position, and all other deflectors being normally in non-deflecting position, each deflector being shiftable upon completion of a series circuit through its magnet and brush or brushes.

16. In a machine of the character described, in combination, means for feeding record cards having group designating perforations in one or more columns, a series of receiving stations, a control device at the first station for analyzing the group desig-

nating perforations and preventing passage of all cards not of a predetermined group, and a control device at each succeeding station to further analyze and distribute the cards of the group, each of said control devices including a magnet, one or more contact brushes, and a deflector

being operable when, and only when, a series circuit is completed through its magnet and its brush or brushes. 10

In testimony whereof I hereto affix my signature.

JAMES W. BRYCE.
